ARTICLE SUPPORT

Robert W. Rosendale, Westfield, N. J., assignor to
Western Electric Company, Incorporated, New
York, N. Y., a corporation of New York

Application August 3, 1944, Serial No. 547,923

3 Claims. (CL 173—361)

1

This invention relates to article supports, and more particularly to bases for electrical units and the method of making the same.

Numerous electrical units, such as vacuum tubes, include bases formed of moldable material in which given numbers of hollow terminal pins are disposed for receiving the leads of the electrical elements in the units. The leads are soldered or partially embedded in solder in the hollow terminals and the life of the units oftentimes depends upon the maintenance of the electrical connections between the leads and their terminals. It has been found important, therefore, that the terminals be positively held against rotation in their apertures to assure against breakage of the leads embedded therein.

Objects of the invention are to provide a base for an electrical unit wherein, through the aid of an efficient method, the terminals are locked against rotation.

With these and other objects in view, the invention comprises a base for an electrical unit which is constructed through the successive steps of forming an annular groove in one surface of the base with an aperture in the base at the groove to receive a hollow terminal, and forming the adjacent end of the terminal to force portions thereof outwardly into engagement with the said surface and force other portions thereof into the groove.

Other objects and advantages will be apparent from the following detailed description when considered in conjunction with the accompanying drawing, wherein

Fig. 1 is a fragmentary front elevational view of the base and terminals about to be assembled by an apparatus through the aid of which the method may be practiced;

Fig. 2 is an enlarged end elevational view of one of the forming tools of the apparatus shown in Fig. 1;

Fig. 3 is a fragmentary sectional view taken substantially along the line 3—3 of Fig. 2;

Fig. 4 is a top plan view of the base after the terminals have been assembled therein, and

Fig. 5 is a fragmentary sectional view taken along the line 5—5 of Fig. 4.

In the present embodiment the base, indicated at 10, selected to illustrate the invention is for an electrical unit, namely a vacuum tube, and is cylindrical in general contour, with a closed end 11 having inner and outer surfaces 12 and 14. In the present illustration four hollow terminals 15 are to be assembled in the base 10, these terminals being identical in structure and including

shoulders 16 positioned short of their upper ends. The machine illustrated in Fig. 1, through the aid of which the method may be practiced for assembling the terminals in the base 10, includes a support 17 with a circular arrangement of apertures 18 therein formed to receive the terminals 15. The shoulders 16 of the terminals, when in position for assembly, will rest upon an upper surface 19 of the support 17. Apertures 20 are formed in the end 11 of the base 10 to receive the terminals 15, these apertures being disposed in circular arrangement as illustrated in Fig. 4. An annular groove 22, of a given depth illustrated in Fig. 5, extends transversely of the apertures 15 20 for a purpose hereinafter described.

The upper portion of the apparatus shown in Fig. 1 illustrates a reciprocate head 23 upon which is mounted a support 26, the latter having apertures 27 in circular arrangement therein to receive reduced ends 28 of forming tools 29. The forming tools 29 are identical in structure and are provided with locating pins 30 to assure their accurate mounting in the support 26. The lower ends of the tools 29 are identical in structure and 25 are of the contours illustrated in Figs. 2 and 3. Considering the tool shown in Figs. 2 and 3, a rounded, somewhat conical, end 32 thereof is receivable in the upper end of its respective terminal 15, the surface thereof merging into a rounded annular surface 33 to jointly cause the inner end of its respective terminal to be bent outwardly, as indicated at 34, until its leading edge engages the surface 12. At opposing sides of the projecting end 32 arcuate forming portions 35 36 are disposed, these portions having widths substantially equal if not smaller than the width of the groove 22, with sharp cutting edges 37 to cut portions 38 and cause these portions to be forced into the groove 22, as illustrated in Figs. 4 and 5.

As a result of the method the base for an electrical unit is provided with apertures to receive terminals the inner ends of which project into the base, distances, limited by the shoulders 16 which rest upon the surface 19 of the support 17 during the forming of the inner ends of the terminals. During the forming operations the inner ends of the terminals are not only bent outwardly so that, in cooperation with the shoulders 16, positive mounting of the terminals in the base is assured, but portions 38 of these inner ends of the terminals are forced into the adjacent portions of the annular groove 22 to lock the terminals against rotation. Furthermore, the locking portions 38 of the terminals are arcuate in gen-

eral contour to closely conform to the adjacent portions of the annular groove so that the terminals are locked against any possible rotary movement.

The method steps therefore include the forming of the base with an aperture or apertures to receive hollow terminals, a groove being formed in one surface of the base transversely with respect to the apertures, after which the terminals are inserted in the apertures, their adjacent ends bent outwardly, and portions thereof pressed into the groove to lock the terminals against rotation.

It should be understood that, although the terminals 15 and their respective forming tools are shown and defined as being of respectively like contours, they may vary in diameters as is oftentimes necessary.

Although specific improvements of the invention have been shown and described, it will be understood that they are but illustrative and that various modifications may be made therein without departing from the scope and spirit of this invention as defined by the appended claims.

What is claimed is:

1. A base for an electrical unit comprising a body having a circular arrangement of apertures therein and an annular groove in one surface thereof traversing the apertures and being smaller in width than the diameters of the apertures, and hollow terminals disposed in each of the apertures with certain portions of their adjacent ends bent outwardly into engagement with the said surface and other portions thereof forced into the annular groove.

2. A base for an electrical unit comprising a body having a circular arrangement of apertures of varied diameters therein and an annular groove in one surface thereof traversing the apertures

and being smaller in width than the diameter of the smallest aperture, and hollow terminals of varied diameters disposed in their respective apertures with certain portions of their adjacent ends bent outwardly into engagement with the said surface and other portions thereof unbedded in the groove.

3. A base for an electrical unit comprising a body having a terminal receiving aperture therein and substantially diametrically opposed recesses in one surface of the body opening into the aperture and being of equal depths throughout their lengths and breadths, and a hollow cylindrical terminal, having a shoulder intermediate its ends, disposed in the aperture a distance limited by the shoulder engaging one surface of the body and having portions of its adjacent end forced outwardly into engagement with the other surface of the base and substantially diametrically opposed portions thereof forced into the recesses to secure the terminal against rotation in the aperture of the base.
